CLAIM

The ornamental design for a flower pot cover, as shown and described.

DESCRIPTION

FIG. 1 is a perspective view of a flower pot cover showing my new design;

FIG. 2 is a typical side elevational view thereof;

FIG. 3 is a top plan view thereof;

FIG. 4 is a bottom plan view thereof;

FIG. 5 is a side elevational view of a second embodiment, the only difference over the first embodiment being in the edge treatment;

FIG. 6 is a side elevational view of a third embodiment, the only difference over the first embodiment being in the edge treatment;

FIG. 7 is a perspective view of a fourth embodiment of the flower pot cover shown in FIG. 1;

FIG. 8 is a typical side elevational view thereof;

FIG. 9 is a top plan view thereof;

FIG. 10 is a bottom plan view thereof;

FIG. 11 is a side elevational view of a fifth embodiment, the only difference over the fourth embodiment being in the edge treatment;

FIG. 12 is a side elevational view of a sixth embodiment, the only difference over the fourth embodiment being in the edge treatment;

FIG. 13 is a side elevational view of a seventh embodiment, the only difference over the fourth embodiment being in the edge treatment;

FIG. 14 is a perspective view of an eighth embodiment of the flower pot cover shown in FIG. 1;

FIG. 15 is a typical side elevational view thereof;

FIG. 16 is a top plan view thereof;

FIG. 17 is a bottom plan view thereof;

FIG. 18 is a side elevational view of a ninth embodiment, the only difference over the eighth embodiment being in the edge treatment;

FIG. 19 is a side elevational view of a tenth embodiment, the only difference over the eighth embodiment being in the edge treatment; and,

FIG. 20 is a side elevational view of an eleventh embodiment, the only difference over the eighth embodiment being in the edge treatment.
